UNITED STATES PATENT OFFICE.

WILLIAM G. KENDALL, OF NEWARK, NEW JERSEY.

COMPACT EJECTOR FOR VANITY CASES.

Application filed January 11, 1927. Serial No. 180,440.

This invention relates to compact ejectors for vanity cases and has for an object to provide an improved construction wherein means are provided for normally holding a compact and its supporting plate in a vanity case while permitting a ready swinging movement of the compact from the vanity case.

Another object of the invention is to provide an ejector for vanity cases wherein a swinging plate or bar extends normally across the bottom of the vanity case and acts to swing the compact and compact carrying plate out of the case when moved from its normal position.

A further object, more specifically, is to provide a swinging ejector bar pivotally connected with a vanity case and extending across the same and formed with means for normally holding the compact plate in the vanity case while also presenting a structure readily swingable out of or partly out of the case.

In the accompanying drawing—

Figure 1 is a top plan view of part of a vanity case with the lid shown open and with an embodiment of the invention applied thereto.

Figure 2 is a view similar to Figure 1 but showing the compact and compact plate removed.

Figure 3 is a sectional view through Figure 1 on line 3—3.

Figure 4 is a view similar to Figure 1 but showing a slightly modified form of ejector and also a different form of casing.

Figure 5 is a sectional view through Figure 4 on line 5—5.

Referring to the accompanying drawing by numerals, 1 indicates a vanity case which is provided with a hinge 2 having a suitable pintle 3 whereby the lid 4 is hingedly connected to the body 1. The body 1 is provided with a catch 5 adapted to receive part of the lid 4 for locking the same closed, said catch being carried by a vertical bar 6 supported by the spring 7 and provided with a thumb member or button 8 extending through body 1. Whenever the button 8 is pressed inwardly, catch 5 will move inwardly and thereby release the lid 4. Bar 6 extends below the spring 7 preferably and is provided with a small raised portion 9 whereby a shoulder is provided for receiving the projection 10 on the ejector bar

11. The ejector bar 11 is provided with a vertical or upstanding member 12 bent slightly inwardly at 13 and at 14 bent to form an overhanging shoulder whereby it may be readily grasped and swung to the left in Figure 3 and in this way crowd the bar 11 to the left in Figure 3, said crowding being only for a short distance and sufficient to cause the extension 10 to move from beneath the projection 9. At the opposite end 60 of the ejector bar or ejector member 11 to the extension 12 is arranged a vertical portion 15, which at the lower end in Figure 3, is spaced a slight distance from the case or body 1 so as to permit the bar 11 to 65 be crowded to the left as just described. The upper part of the vertical portion 15 is turned over for forming a knuckle 16 and said knuckle surrounding the pintle 3 and 70 in appearance forming part of the hinge. 75 The portion 15 is also provided with a pair of pressed out lugs or spurs 17 which project over a shoulder 18 of the compact plate 19. The plate 19 carries a cosmetic pad 80 20 of face powder, rouge or other cosmetic. The spurs 17 act as retaining means for holding the compact plate or holder 19 in place and co-acting with these spurs are holding members 21 and 22. These holding members are formed identical and are preferably integral with resilient extensions 85 23 and 24 of the extension or portion 12 which is also formed integral with the bar 11. The holding members 21 are spaced 90 ears which straddle the bead or projection 25 of plate 19 so that the plate 19 and the compact 20 carried thereby are supported on the bar 11 by member 17 and members 21 and 22. When the bent end 14 is grasped 95 and pulled to the left in Figure 3, the parts are crowded over toward the hinge 16 sufficiently to allow the extension 10 to move past the projection 9. This will permit the parts to be swung to an open position as 100 shown in dotted lines in Figure 3. After a new compact and compact plate have been inserted in the injector, the parts are merely forced down until the extension 10 snaps beneath the extension 9. 105

In Figures 4 and 5, a modified form of the invention is shown wherein the device is adapted to a different form of vanity case 26. In this form of vanity case, the body 27 is provided with a turned over flange 28 at 110 the periphery, said flange accommodating

- a wire 29 which forms a pintle for the hinge 30 and which also is preferably bent slightly at 31 for accommodating the turned over end or knuckle 32 of the ejector plate 33.
- 5 At the end opposite to the knuckle 32, plate 33 is bent at 34 and then again at 35 for presenting a finger hold. The plate 33 is resilient and the bent portion 34 is adapted to be snapped beneath the knuckles of the 10 hinge 30 when the plate is in its operative position. The compact plate 36 with its compact may be placed in position as shown in Figure 5 with part of the compact projecting beneath the flange 28 and part beneath the turned over ends 34 and 35. This 15 will effectively hold the compact plate and its compact in the case 26 until the plate 33 has been swung to an outer position as shown in dotted lines in Figure 5 whereby 20 the compact plate may be removed and a new one substituted if desired. After a new plate has been substituted, the parts are merely forced downwardly into the position shown in Figure 5 and the end 34 will 25 snap beneath the hinge 30, thus resiliently locking the parts in body 27.

What I claim is:

1. The combination with a vanity case having a hinge provided with a pintle and 30 a body provided with a catch, of a plate having a knuckle surrounding said pintle, said plate extending across the bottom of said body, and means forming part of the 35 plate interlocking with the catch structure of the vanity case for normally holding the plate against the bottom of the body.
2. The combination with a vanity case having a hinge provided with a pintle and a body provided with a catch on the diametrically opposite side to the hinge, said 40 catch having a projection near the bottom of the body, of a compact holder and ejector comprising a bar extending across the bottom of said body and at one end formed with a knuckle surrounding said pintle and 45 at the opposite end with an extension normally projecting below said projection, and hand operated means connected to said bar for shifting the same longitudinally sufficiently to cause said extension to be dis-

engaged whereby the bar may be swung out of the body of the vanity case.

3. The combination with a vanity case having a catch formed with a projection near the bottom, of a hingedly mounted 55 ejector provided with an extension fitting normally beneath said projection and with a hand operated member connected with the ejector near said extension whereby the ejector may be moved slightly so as to be 60 disengaged and then swung to a position out of the vanity case.

4. An ejector for vanity cases comprising an ejecting bar, a knuckle formed at one end of the bar, a pair of laterally extending 65 arms formed at the opposite end of the bar, an extension formed also at said opposite end of the bar, each of said arms being provided with a substantially U-shaped structure adapted to straddle part 70 of the compact holder for normally holding the holder in the vanity case, and a hand operated member adapted to be grasped and pulled for swinging the bar and the compact held by said U-shaped structure whereby the 75 compact will be moved out of the vanity case.

5. A compact holder and ejector for vanity cases comprising a bar provided with a hinge knuckle at one end, a pair of holding 80 spurs at the end carrying the knuckle, a pair of resilient arms at the opposite end, each of said arms having a straddling holding member for straddling part of the compact holder, a hand operated member for 85 moving said bar out of a vanity case, and a projector co-acting with certain parts of the vanity case for normally holding the bar in the body of the vanity case.

6. In a vanity case a compact holder and 90 ejector comprising a flat bar having a coiled hollow portion at one end, said coiled end being also provided with a pair of holding spurs, a pair of integral laterally extending springs at the opposite end to said bar, each of said springs having a pair of U-shaped ears, and an extension at the center of said arms acting to hold the bar in position when in use.

WILLIAM G. KENDALL.
